UNITED STATES PATENT OFFICE

171,886

LIPSTICK HOLDER

Sophie Frydlander, Paris, France

Application April 28, 1951, Serial No. 15,006

Claims priority, application France
December 22, 1950

Term of patent 3½ years

(Cl. D86—10)

To all whom it may concern:

Be it known that I, Sophie Frydlander, a citizen of the Republic of France, residing at Paris, France, have invented a new, original, and ornamental Design for a Lipstick Holder, of which the following is a specification, reference being had to the accompanying drawing, forming a part hereof.

Fig. 1 is an elevational view of a lipstick holder showing my new design; and

Fig. 2 is a bottom plan view thereof.

I claim:

The ornamental design for a lipstick holder, as shown.
